FISH LURE

Jack K. Smithwick, P.O. Box 1205,
Shreveport, La. 71102

Filed Mar. 7, 1969, Ser. No. 16,108

Term of patent 14 years

Int. Cl. D22—07

U.S. Cl. D22—27

FIG. 1 is a side elevation view of a fish lure incorporating my new design.

FIG. 2 is a front end elevation view of the fish lure depicted in FIG. 1.

FIG. 3 is a side elevation view of the fish lure shown in FIG. 1 as the lure appears when viewed from the opposite side thereof from the side shown in FIG. 1.

FIG. 4 is a rear elevation view of the fish lure depicted in FIG. 1.

FIG. 5 is a top plan view of the fish lure depicted in FIG. 1.

FIG. 6 is a bottom plan view of the fish lure depicted in FIG. 1.

I claim:

The ornamental design for a fish lure, substantially as shown.
